UNITED STATES PATENT OFFICE.

KENNARD J. KORNBAU, OF NEW YORK, N. Y.

WALL TIE FOR MASONRY VENEER WORK.

Application filed October 1, 1927. Serial No. 223,291.

The object of my invention is to provide a tie of this character which will hold securely and firmly when set in a wall and be absolutely reliable under all conditions, and 5 a further object is to provide a tie which will nest when packed so as to require a minimum space for storage and shipping. These and other objects are accomplished by my invention, one embodiment of which is 10 hereinafter more particularly set forth.

For a more particular description of my invention, reference is to be had to the accompanying drawings, forming a part hereof, in which

15 Figure 1 is a sectional view of a wall provided with my improved tie.

Figure 2 is a plan view of my improved tie.

20 Figure 3 is a longitudinal view of the same.

Figure 4 is a diagonal section of the tie in place, the section of the metal being taken on the line 4—4 of Figure 2, looking in the direction of the arrows.

25 Throughout the various views of the drawings, similar reference characters designate similar parts.

My improved tie 1 is adapted to be set in 30 mortar 2 between bricks, stones or other masonry material 3 set in the usual way, and this tie projects from said masonry and is adapted to be secured to other material as beams, joists or what not, 4 by nails 5, in the conventional manner.

35 It is essential that the tie 1 should have gripping surfaces 6 connected by an intermediate smooth portion 7 which may be readily bent according to the requirements of the place of its use or which may remain 40 straight as shown in Figure 1. In order

that the rough portions 6 may at all times preserve their true shape and perform their function regardless of any stresses or strains that may be imposed on the tie, the corrugations are made in a herring bone pattern, 45 as indicated in Figure 2, and the parts of the corrugations which rest against the mortar 2, to prevent the tie from coming out, are made very steep, as shown at 8, the slope being at substantially eighty or 50 eighty-five degrees to the surface plane. It is desirable that there be a little slope so that one tie may nest in another when the same are packed.

It is also desirable that, at suitable locations, nail holes 9 be provided through which the nails 5 may be applied, as indicated in Figure 1, or in any other desired way.

55 As this tie is used in the ordinary manner, further description of its use is unnecessary.

While I have shown and described one embodiment of my invention, it is obvious that it is not restricted thereto, but that it is 60 broad enough to cover all structures that come within the scope of the annexed claim.

Having thus described my invention, what I claim is:

70 A tie with ends roughened along herring bone pattern corrugations, certain sides of said corrugations being made steep so as to afford a mortar engaging surface which will secure the tie firmly in place when the same is in use.

75 In testimony whereof, I have hereunto set my hand this 23rd day of September, 1927.

KENNARD J. KORNBAU.
